GRAINING ROLL

Guido von Webern, Dayton, Ohio, assignor to
Oxford Varnish Corporation, Detroit, Mich., a
corporation of Michigan

Original application April 19, 1930, Serial No.
445,576. Divided and this application January
22, 1934, Serial No. 707,787

3 Claims. (Cl. 101—401.1)

This invention relates to pattern roll for printing designs such as wood grain, marble and the like, and is a division of my copending application, Serial No. 445,576, filed April 19th, 1930. The essential object is to provide cylindrical form having thereon, in effect, a circumferentially continuous pattern, in which the joint or joints of the pattern are substantially imperceptible.

A further object is to provide an improved printing roll with a substantially continuous pattern, that is, for all practical purposes, a jointless grained pattern.

Another object of the invention is to provide an improved graining or printing roll, having substantially the entire printing area thereof image bearing, such image comprising grain or similar non-repeating lines of varying prominence direction and tone and having the pattern joined substantially along the more prominent lines to provide a substantially continuous pattern which, for all practical purposes, is jointless.

The requirements of pattern rolls for use with present-day graining methods differ from the roll requirements occurring in textile, wallpaper and other similar types of work, in that the patterns for textiles, paper, etc. are of conventional design, generally more or less open, and the design units repeat, whereas there is no repetition of design in natural wood or marble. Joints in such rolls are readily made either in open parts or by cutting the repeating units at identical positions.

In preparing rolls for wood graining work in the past, the joints in the pattern were made without regard to the design and the ends of the pattern were spaced a considerable distance apart and the space therebetween was hand tooled subsequent to the etching of the pattern. The disadvantages of such a roll are numerous. First, the joints were readily apparent; second, the hand tooled portion of the roll was at the best a futile reproduction of the photo-engraved portion and destroyed the advantages gained by such a photographic reproduction.

The roll of the present invention overcomes the disadvantages found in graining rolls of the past. The improved roll carries a photographically reproduced pattern throughout its entire length. This is accomplished by providing the roll with a pattern which is joined along the more distinct grain lines, as, for instance, in the case of wood having very distinct grain patterns, such as the "flake" of quartered oak, the pattern is joined to the flake lines. Where this is no longer possible, because the flake stops, the pattern is joined along diagonal or circumferential lines, following the

dense grain lines or lines of sharp tonal variations, as much as possible, and joining the pattern along such lines or lines parallel thereto.

To better illustrate the invention, I have shown the improved roll, together with a diagrammatic illustration of a manner on which the roll may be made in the accompanying drawing. In the drawing, Fig. 1 is a perspective view of my improved roll, the joint line being diagrammatically indicated thereon in heavy lines; Fig. 2 is a plan view of a suitable sample, such as a wood board; Fig. 3 is a divided photographic print made from a selected area on the board; Fig. 4 is a view showing the two parts of the print in partly overlying relation to each other for matching and cutting; Fig. 5 shows the two sections of the print after the match cutting is completed; Fig. 6 is a view similar to Fig. 5, showing a special grain pattern; Fig. 7 is a view of the print rejoined along the original severing lines; Fig. 8 is a perspective view of a roll of different dimension than that shown in Fig. 1.

Referring again to the drawing, and first to Fig. 2, I have shown at 11 a suitable wood sample, such as a finished board, having in general the desired grain characteristics. It is possible on a great many wood samples to find about the same general grain characteristics at one part of the board as may be found in another. For example, suppose one finds such generally similar grain characteristics 30" apart, then by my method, a single resist strip may be made to cover a roll having a 30" circumference.

It will be seen from Fig. 2 that there is a general similarity of grain effects in proximity to the two broken vertical lines *x* and *y*. Having found these two similar areas, I make a photograph of the board embracing both areas, say a photograph in the proportions indicated by the broken line *v*. A print of such photograph will, of course, cover considerably more than the entire circumference of the roll, assuming the lines *x* and *y* are 30" apart. Fig. 3 represents a print made from such a photograph of the area within the line *v*, which print has been severed at *a*—*a'*, so that the two ends which are substantially similar may be matched up by experimental cutting, such a method as is claimed and described in my copending application, heretofore mentioned, or in any other manner.

It will be seen that if the two sections of the print of Fig. 3 are fastened on a matching board 4, face up, with the severed edges *a* and *a'* a measured distance from each other, equal to the circumference of the roll, any part of the zone

lying between the lines *b* and *b'*, Fig. 4, may be used to effect matching or registration of the grain lines on the top section with those of the underlying section. This may be done by simply 5 cutting back the top section to any distance within this zone of overlap of the two prints, until the desired match is effected.

Matching and outlining may be carried out as described in my copending application, heretofore mentioned. Briefly, the matching is done 10 as follows: One first turns back the uppermost free edges *b* for example, and finds prominent lines, such as tone lines, grain lines, or the like, which substantially coincide on both prints, and 15 he now cuts along such lines, as indicated at 6, where the grain lines are actually crossed, and at 7, where the more prominent grain lines are actually followed. When following the prominent lines such as the grain lines, the direction 20 of cut is determined by these lines alone and may be actually parallel to the edges *a* and *a'*, but when crossing the grain lines, the cut is made diagonally for the most part because it is much less easy to detect a joint on a diagonal or circumferential line than a joint on a line parallel to the axis of the roll, assuming the grain lines 25 run generally circumferentially.

This outline cutting, as mentioned, is largely 30 a matter of experiment, and several cuts may have to be made before a satisfactory match has been found. For example, having found that the cutting lines 6 and 7 on Fig. 5 do not result in a true alignment of grain lines of a satisfactory 35 grain line blending, another cut may be made as along the dotted lines 6', 7', reducing the length of the top section of the print, as will be obvious. The limit of cutting back the top section is, of course, the edge *b'* of the bottom section.

Having thus obtained an approximate match 40 between what were previously the opposite ends of the print, the two sections of the print may now be rejoined in their original position, whereupon if the two ends of the print have been match cut, the ends of the rejoined print will be 45 found to fit into each other with the print curled up into a circle.

A sheet of the usual carbon resist previously 50 exposed from the same plate or film that was used to produce the print, outlined and/or cut as above described, and which is also marked in any suitable way as on the back side thereof to determine the position of the grain thereon, may now be secured in the usual way to the roll surface to be etched. The outlined and/or cut pattern print also marked similarly to the resist 55 may now be used to indicate on the resist where the etching should stop. For example, any suitable line may be drawn on the resist or the blank portions of the roll, using the match cut or outline on the print as a pattern and the resist at one side of the match line (toward the nearest margin) painted out carefully, as with asphaltum, in substantial conformity to the outline of the print. The opposite end of the resist and 60 the side margins are, of course, also painted out or otherwise treated to protect the roll surface not to be etched. The surface of the roll within the protected area is now etched with a suitable agent.

70 In the illustration shown in Fig. 6, it will be seen that wood patterns having very definite cross grain characteristics, such as quartered oak, may be matched somewhat easier than plain walnut or mahogany grain, which latter have 75 no such peculiar grain marks. In Fig. 6, the so-

called flakes of quartered oak are indicated at 10 on the top print and 11 on the underlying print. The cutting lines in this case follows along the flakes, and as to the top print, the cutting lines will follow along that edge of the 15 flake which is toward the free or inner edge of the top print, whereas the flake on the print underneath is followed on the side of the flake toward the free end of this under print. Thus, 20 when the resists are properly applied to the roll and the roll etched, the grain effect will be a natural one and the joint practically invisible. The same general principle as shown in Fig. 6 applies 25 to cutting the print in butt or burl walnut and like woods having rather peculiar grain or tone marks; for example, the burl lines in burl walnut are followed the same as the flake lines in quartered oak. In marble the cleavage veins or lines are generally followed.

Having thus matched the pattern ends by an 30 irregular outline, the edges *a* and *a'* may now be rejoined, as shown in Fig. 7. It will be seen that a resist properly marked for location according to the rejoined print and having the same grain pattern will exactly cover a 30" roll. Furthermore, two resists that are, for example, cut or painted out or otherwise more identical with the rejoined print, and are identical in pattern will completely cover a 60" cylinder, that is, one having a circumferential length equal to twice the 35 dimension A of Fig. 3. In either case the grain at the ends of such resists will substantially match.

Assuming the resist has been properly located 40 on the cylinder and properly outlined, the roll 45 surface underlying the resist is now etched to the proper depth and fineness of tone. In case only part of the roll is covered, the copper at the ends of the resist is protected by a coating of paint. Before applying a second resist to the 50 opposite surface of the roll, the roll is first cleaned of all the protecting paint and the residue of the etching operation. The second resist does not necessarily have to be outlined since the etched portions of the roll serve as a very definite guide. The previously etched surfaces, at 55 least at the two ends of the etched area, are, of course, covered with protective paint before starting to each the second resist. From this point, the etching process, as previously outlined, may be repeated and afterward the entire roll is cleaned of etch residue and paint. Some hand tooling may have to be done where there are blank or unetched spaces at the joints, but if the 60 above steps are carefully followed, this hand tooling is practically a negligible item.

In the above detailed exemplary description it is assumed that the resist will cover either the entire or half the circumference of the roll. This, however, is not essential since the first resist may 65 cover any portion of the roll, say all but a few inches of the circumference, and the intervening space filled in by etching through a resist section corresponding to any part of the original board or sample, or an entirely different board or sample. Likewise, where a plurality of resists are used, such resists may be cut to match the next 70 adjacent resist and all of the resists etched simultaneously.

I may also select a subject having generally 75 similar grain areas spaced longitudinally of the board, but which spacing does not bear any integral relation to the circumferential length of the roll as does the pattern shown in the drawing. Suppose, for example, the generally simi-

lar areas are spaced a few inches less than the roll measures circumferentially. In such case, I start with a photograph and divide it substantially as shown in Fig. 2, but instead of overlapping the ends b and b' as in Fig. 3, I then fasten the opposite edges, a and a' to the matching board, spaced exactly the circumferential length of the roll, leaving the edges b and b' separated. Then a second print section is inserted between the spaced edges b and b' ; underlying both these edges. The second print is made from any sample having grain characteristics generally similar to those at the ends of the divided strip. After this the match outlining may be accomplished substantially as before, for example by cutting back both edges b and b' , until the grain lines of the two top print sections register with the exposed grain lines on the print, underneath. Incidentally, the second print may lie on top of the edges b and b' , in which case this second print receives the match cutting. Afterward the print forming the fill-in is properly marked to determine its position on the roll. The two original print sections are then rejoined to form a pattern for outlining one resist, and the second print, which has also been marked for position is used to locate the resist properly on the unetched portion of the roll.

The two resists thus formed completely cover the roll, and, assuming the distance A has been measured accurately and the match cutting accurately performed, a continuous pattern effect is obtained on the roll by etching, as above described. This variation of the method is particularly valuable where the pattern effects desired are formed on two separate board, marble, etc.

samples and/or where a non-repeating pattern is desired.

In special cases, I may also use the resist itself for the photographic copy with which the match outlining is effected.

No detailed description of the actual steps in forming an etch resist or in the method of etching a roll therethrough has been given, but reference may be made to the patent of J. P. Henry, No. 1,548,945, owned by the assignee hereof, for a suitable method for use in intaglio printing. Any of the other known methods, for example half tone, may also be used.

I claim:

1. A graining roll comprising a substantially cylindrical printing member having a metallic pattern carrying surface, the surface having etched thereon a pattern simulating wood grain, the pattern being non-repeating and the grain lines throughout the entire circumference being unbroken in simulation of natural wood grain.

2. A graining roll having a photomechanically reproduction of a wood or similar grained article thereon, such reproduction being joined to form a continuous non-repeating pattern, the joint being effected at prominent lines in the reproduction whereby for practical purposes the pattern is jointless.

3. A graining roll having a reproduction of a natural object thereon which object comprises a non-repeating pattern having prominent irregular lines thereon of varying directions and tones, said roll having the pattern joined along certain of said prominent lines to produce a continuous pattern circumferentially of the roll.

GUIDO von WEBERN.
